UNITED STATES PATENT OFFICE.

HARRY R. BUTLER, OF PELHAM MANOR, NEW YORK, ASSIGNOR TO THE YALE & TOWNE MANUFACTURING COMPANY, OF STAMFORD, CONNECTICUT.

TROLLEY-TRACK HANGER.

1,411,234.

Specification of Letters Patent. Patented Mar. 28, 1922.

Application filed May 27, 1921. Serial No. 473,067.

To all whom it may concern:

Be it known that I, HARRY R. BUTLER, a citizen of the United States, and a resident of Pelham Manor, in the county of West-
5 chester and State of New York, have invented certain new and useful Improvements in Trolley-Track Hangers; and I do hereby declare the following to be a full, clear, and exact description of the invention, such as
10 will enable others skilled in the art to which it appertains to make and use the same.

My invention relates to an improvement in trolley track hangers, the object being to provide a hanger that can be applied to an
15 I-beam track and adjusted to any position thereon and clamped thereto without drilling or otherwise cutting said beam, and it consists in the parts and combination of parts as will be more fully explained and pointed
20 out in the claims.

In the accompanying drawings, Figure 1 is a view in end elevation of the track and partly in edge elevation and partly in section of the hanger and supporting bracket
25 for the latter, and Figure 2 is a view in side elevation of the same.

5 represents the track which is in the form of an I-beam, and 6 is a one piece malleable or steel casting having hook shaped ends 7.
30 The hook shaped ends 7, as shown in Figure 1 are oppositely disposed at the underside of the hanger to receive the opposite side edges of the upper flange of the I-beam, the space between the hooks and body of the
35 hanger being of ample size to receive the upper flange of the beam, and permit of the free adjustment of the hanger on the beam. The hanger 6 is provided centrally with a threaded hole for the holding bolt 8, the
40 lower end of which is adapted to engage the upper surface of the top flange of the I-beam
5 and clamp the holder to the beam, after of course the hanger has been adjusted to its proper position on the beam.

45 9 is the supporting bracket which in the present instance is V-shape, with a flattened apex, the latter having an opening through same for the passage of the bolt 8, which latter not only clamps the hanger to the
50 I-beam, but also secures the hanger to the bracket. The bolt opening through the

hanger 9 is preferably not threaded and slightly larger than the bolt, and is clamped against the top surface of the hanger 6 by the cheek or lock nut 10, the bolt 8 being
55 sufficiently long to permit of a movement of the nut 10 thereon to release the bolt so that the latter may be turned to engage or disengage the I-beam as shown.

In assembling the parts, the hanger 6 is
60 applied at the end of the I-beam and moved lengthwise the latter to its proper position. This may be done before the bracket or bolt
are assembled on the hanger, or after as
65 preferred, and after the parts have been
assembled and the hanger properly located
on the beam, the parts are locked together
by first screwing in the bolt to engage the
I-beam and then screwing down the nut 10
70 to clamp the bracket to the hanger.

Having fully described my invention what I claim as new and desire to secure by Letters-Patent, is:—

1. The combination of an integral hanger having downwardly turned hook shaped
75 ends adapted to engage the opposite edges of the upper flange of an I-beam and also provided with a threaded hole, a threaded bolt passing through said hole and adapted to be adjusted therein to engage the I-beam
80 and a bracket having connection with the bolt for supporting the hanger, the bolt being independent of the bracket and adjustable therein.

2. The combination of a hanger provided
85 on its under side with oppositely disposed hook shaped ends to receive and support the top flange of an I-beam, and also provided with a threaded hole, a threaded bolt passing through said hole and adapted to engage
90 said I-beam for clamping the hanger to the latter, a supporting bracket having a hole for the bolt, and a nut on the bolt for clamping the bracket to the hanger.

In testimony whereof, I have signed this
95 specification in the presence of two subscribing
witnesses.

HARRY R. BUTLER.
